UNITED STATES PATENT OFFICE.

JOSEPH MAKOWSKI, OF FORT WAYNE, INDIANA.

TOILET ARTICLE.

1,118,432.

Specification of Letters Patent.

Patented Nov. 24, 1914.

Application filed July 7, 1914. Serial No. 849,500.

To all whom it may concern:

Be it known that I, JOSEPH MAKOWSKI, a subject of the Czar of Russia, residing at Fort Wayne, in the county of Allen and State of Indiana, have invented certain new and useful Improvements in Toilet Articles, of which the following is a specification.

This invention relates to certain new and useful improvements in toilet articles.

10 The primary object of this invention is to combine a hair brush and comb in a unitary structure, and whereby the usual brush handle is adapted for manipulating both the brush and the comb in the hair drying operation.

15 A further object is to provide a hair brush with a removable comb positioned for immediate use longitudinally of the comb back, such comb being readily removable when desired.

20 A still further object is to provide a removable comb mounting upon a hair brush and in providing a comb which is removably fitted within said bracket.

25 With these general objects in view and others that will appear as the nature of the invention is better understood, the same consists in the novel construction, combination and arrangement of parts as will be herein- 30 after more fully illustrated in the accompanying drawings, and pointed out in the appended claims.

35 In the accompanying drawings forming a part of this application and wherein like numerals of reference designate corresponding parts throughout the several views:— Figure 1 is a side elevation of the device, the comb holding bracket being partially broken away. Fig. 2 is a top plan view of 40 the device, and, Fig. 3 is a transverse sectional view taken upon line III—III of Fig. 2.

45 Referring more in detail to the drawings, it will be noted that the hair brush 10 is provided of substantially the usual construction and having the bristles 11 thereof secured to the brush back 12 which is extended into a handle 13 formed integral therewith.

50 A metallic bracket 14 is longitudinally positioned centrally upon the brush back 12 and consists of a metallic strip having one end thereof bifurcated, and forming laterally projecting arms 15 which are curved and have their hooked ends 16 adapted to fit around the base portion of the handle 13. The other end of the bracket strip is pro-

vided with a depending hook 17 having a lock screw 18 threaded therethrough and adapted to bear upon the curved free end 19 of the brush back 12. The bracket strip 14 is substantially U-shaped in cross-section as best illustrated in Fig. 3 for substantially its entire length, and forms a comb-receiving groove open at the top thereof and having its sides 20 slightly converging upwardly. A comb 21 has its base portion 22 slightly tapered conforming to and adapted for slidable reception within the strip 14, and between the sides 20 thereof. The comb back is also preferably provided with longitudinal grooves 23 upon opposite sides thereof and adapted to receive the upper edges 24 of the strip sides 20. The strip 14 is provided with an upwardly-struck lug 25 upon the base portion of the strip which is adapted by its own resiliency to be received within a bottom socket and recess 26 in the comb back.

From this detailed description of the device, it will be at once evident that a removable bracket is attached to the brush back while the comb 21 may be readily slid into the bracket as well as removed therefrom. The comb however, is retained from accidental displacement by means of the closely fitting sides 20 of the bracket and also by the retaining lug 25 so that the comb and brush may be readily operated by the handle 13 or the comb may be detached if desired.

While the forms of the invention herein shown and described are what are believed to be preferable embodiments thereof, it is nevertheless to be understood that various forms, modifications and arrangement of the parts as shown may be had without departing from the spirit and scope of the invention as claimed.

What I claim as new is:—

1. The combination with a base member 100 provided with a narrowed portion, of a strip member substantially U-shaped in cross-section, diverging hooked arms at one end of the strip adapted for engaging said narrowed portion, a depending hook at the 105 other end of said strip, a set screw carried by said hook and adapted for engaging said base member, and a comb removably positioned upon said strip.

2. The combination with a base member 110 provided with a narrowed portion, of a strip member substantially U-shaped in

cross-section, diverging hooked arms at one end of the strip adapted for engaging said narrowed portion, a depending hook at the other end of said strip, a set screw carried by said hook and adapted for engaging said base member, the sides of said strip being slightly convergent and the base portion thereof provided with an inwardly-projecting struck-up lug, and a comb having a 10 tapered back portion provided with opposite longitudinal grooves and adapted for fitting between said sides of the strip with

the upper edges of said sides in engagement with said grooves, said comb provided with a recess adapted for seating over said struck-up lug when the comb is operatively positioned upon the said base member. 13

In testimony whereof I affix my signature in presence of two witnesses.

JOSEPH MAKOWSKI.
